UNITED STATES PATENT OFFICE.

SAMUEL P. FAIRCHILD, OF SHERIDAN, MONTANA.

FOLDING VEHICLE-STEP.

1,268,335.

Specification of Letters Patent.

Patented June 4, 1918.

Application filed October 12, 1917. Serial No. 196,927.

To all whom it may concern:

Be it known that I, SAMUEL P. FAIRCHILD, a citizen of the United States, residing at Sheridan, in the county of Madison, State of Montana, have invented certain new and useful Improvements in Folding Vehicle-Steps; and I do hereby declare the following to be a full, clear, and exact description of the invention, such as will enable others skilled in the art to which it appertains to make and use the same.

This invention is an improvement in vehicle steps and has particular reference to a folding step for railway cars.

An object of the invention is to provide an improved step the main section of which is supported in its operative position by the pivotal connection between the same and the riser section of the step.

Another object is the provision of a step of this character which is simple in construction, easy to manufacture, readily applicable to railway cars or other vehicles of known construction and effective in carrying out the purpose for which it is designed.

The inventive idea involved is capable of receiving a variety of mechanical expressions one of which for the purpose of illustrating the invention, is shown in the accompanying drawing wherein:—

Figure 1 is a side elevation of the step constructed in accordance with the invention and with the foldable step in its operative position.

Fig. 2 is a similar view with the step in its inoperative position.

Fig. 3 is a front elevation.

Fig. 4 is a bottom plan view.

Fig. 5 is a vertical longitudinal section.

Fig. 6 is a perspective view of the riser section of the step.

In the drawing the numeral 10 indicates the usual stationary steps of a railway car to the underside of the lowermost of which are secured the brackets 11 having bearings 12 for supporting the pivot rod 13 to which the riser section 14 of the foldable step is pivoted. Said section is provided upon its upper edge with bearings 15 receiving said rod 13 and the lower edge of the section intermediate its ends is likewise provided with a bearing 16 extending in the opposite direction from the bearings 15 and has mounted therein the pivot rod or pintle 17 the ends of which extend a distance beyond the ends of the section and are provided

with heads 18, the projecting ends of said rod having sleeves 19 mounted thereon for a purpose which will later appear.

The tread section 20, of the foldable step is pivoted to the rod 17 by means of bearings 21 disposed on each side of the bearing 16 and the edge of the section, upon which said bearings 21 are formed, is also provided with a flange 21' arranged between said bearings and adapted for engagement with the rear face of the riser section 14 when in operative position whereby to aid in supporting said tread section in such position. The forward longitudinal edge of said tread section is provided with a bearing 22 which receives the rod 23 having its ends projecting beyond the ends of said bearing and provided with heads 24.

One of the stationary steps 10 has pivoted thereto, by bearings 25, a U-shaped hanger 26 the side arms 26' of which depend on each side of the steps and have their free ends pivoted to supporting links 27. The forward ends of these links are pivoted to the ends of the rod 23 between the ends of the bearing 22 and the heads 24 and the portions of said links adjacent said pivot points engage the sleeves 19, when the step is in operative position, and thereby support and securely maintain the main section of the step in horizontal position.

One of the side arms 26' of the hanger has preferably secured thereto an operating lever 28 which extends upwardly so as to be within easy reach of the operator and by swinging said lever about the bight portion of the hanger 26 as a pivot it will be apparent that the foldable step may be adjusted to its operative and inoperative positions. Means are further provided for retaining the lever 28 in its adjusted positions and this means preferably comprises a block 29 secured to an adjacent support and having its ends beveled as indicated at 30 and adapted to be engaged by said lever after the step has been adjusted to either position, it being understood that in order to disengage the lever from said beveled ends the same is made resilient so that it may be sprung outwardly.

What is claimed is:—

1. In a device of the class described, the combination, with a plurality of stationary steps; of a foldable step including a riser section pivoted to one of the stationary steps, a tread section pivoted to said riser

section and having the ends of the pivot therefor extending beyond the ends of said sections, a hanger pivoted to another of said stationary steps, and links connecting said 5 hanger with said tread section and adapted to engage the projecting ends of the pivot for said riser and tread sections when the same are in their operative positions.

2. In a device of the class described, the 10 combination with a plurality of stationary steps; of a foldable step including a riser section having its upper edge pivoted to the lowermost stationary step at its outer edge to provide a bearing, a tread section 15 for the foldable step having its rear edge provided with bearings engageable on each side of the bearing of said riser section, a pivot rod extending through, said bearings

and having its ends projecting beyond the ends of said sections, links pivoted to the 20 forward edge of said tread section and engageable with the projecting ends of said pivot rod when the foldable step is not in operative position, a hanger pivoted to said stationary steps and pivotally connected to 25 said links, and a level secured to said hanger and operated to swing the same about its pivot whereby to adjust said foldable step to operative and inoperative positions.

In testimony whereof, I affix my signature in the presence of two witnesses.

SAMUEL P. FAIRCHILD.
